UNITED STATES PATENT OFFICE

98,227

DESIGN FOR A WASHSTAND

John A. Callahan, Detroit, Mich., assignor to Briggs Manufacturing Company, Detroit, Mich.,
a corporation of Michigan

Application April 26, 1935, Serial No. 56,584

Term of patent 14 years

To all whom it may concern:

Be it known that I, John A. Callahan, a citizen of the United States, residing at Detroit, county of Wayne, State of Michigan, have invented a new, original, and ornamental Design for a Washstand, of which the following is a specification, reference being had therein to the accompanying drawing, forming a part thereof, in which there is shown a perspective view of the washstand.

I claim:

The ornamental design for a washstand, substantially as shown.

JOHN A. CALLAHAN.
